UNITED STATES PATENT OFFICE.

ANDREW J. BARRON, OF CINCINNATI, OHIO, ASSIGNOR TO CINCINNATI HORSE SHOE & IRON COMPANY, A CORPORATION OF OHIO.

AUTOMOBILE SPRING-SUPPORTING MECHANISM.

Application filed May 11, 1922. Serial No. 560,062.

To all whom it may concern:

Be it known that I, ANDREW J. BARRON, residing at Cincinnati, Ohio, and a citizen of the United States, have invented certain new and useful Improvements in Automobile Spring-Supporting Mechanism, of which the following is a specification.

This invention relates to platform spring equipment for Ford pleasure cars and trucks, and the particular object in view is to provide mechanism for supporting the front ends of the side or longitudinal springs that will permit ready and quick installation, and that is independent of any superstructure.

With this object in view, the invention resides in the novel construction, combination and arrangement of structural parts, as will be hereinafter fully described in the specification, summarized in the claims, and illustrated in the drawing.

The invention is exemplified, in its preferred form, in the accompanying drawing, like reference characters denoting corresponding parts throughout the several views thereof. Briefly described:

Figure 1 is a top plan view of my improvements in assembled position relative to the longitudinal channels of the chassis or frame of the Ford car;

Figure 2 is a sectional view on the line 2—2, Fig. 1, looking in the direction of the arrows;

Figure 3 is a view in end elevation; and

Figure 4 is a detached detail view of one of the reinforcing members.

Referring, now, in detail to the drawing:

1, 1 designate longitudinal channels of the chassis or frame of the Ford car.

40 The front end of each side spring 2 is supported, at its front end, by operative connection, as shown at 3, with a vertical link 4 on a pin 5 received in a bearing 6 laterally carried by a hanger, which may be

45 formed as a casting, comprising a tapering bottom 7, upright side flanges 8, 8, and a rear wall or vertical flange 9. Said bottom 7 may be provided with a strengthening rib 10. The rear wall 9 is provided with a basal projection 11, forming a shoulder 11', which, when the hanger is in operative position with respect to the channel 1, receives the lower front corner of said hanger, the rear wall 9 of the hanger bearing against

the vertical web of said channel, as clearly 55 shown in Fig. 2.

Each hanger is secured, by means of bolts 12 passing through the rear wall 9 thereof, to the flange 13 of each of two angles, the flanges 14 of said angles being bolted together, upon assembly of the parts, as shown at 15.

In order to prevent warping and twisting out of shape of the channels 1, 1, under strain and stresses, I provide a reinforcing bridge, which is disposed between said channels, and which comprises two angle-bars 16, 16, disposed side by side and united, in the assembled position of the parts, by bolts 17 passing through the depending flanges 18 thereof. The angle-bars 16, 16, rest at their ends, upon the tops of the flanges 14, and, for this purpose, said ends of the angle-bars and said tops of the flanges 14 are correspondingly beveled, as shown at 20.

75 Preferably, two strengthening or reinforcing corner plates 19, 19, which may be triangular in outline, as shown, are interposed between the depending flanges 18, 18 of the angle-bars 16, 16 and between the flanges 14 of the angles 13, and are secured in operative position by the bolts 15 and 17, previously referred to.

In order to make a mechanical and rigid construction, and also to prevent working loose of structural parts, I have provided what I call a filler-member, as shown most clearly in Fig. 4, comprising a top and bottom 20 and 20' and ends 21, 21, the latter projecting beyond the top and bottom, on each side thereof, forming lips 22. This filler-member is adapted to be disposed in the channel 1, as shown in Fig. 2, two of said lips 22 bearing against the outer edges of the flanges 13 of the angles 14.

Having thus fully described my invention, what I claim as new and desire to secure by Letters-Patent is:

1. The combination with the longitudinal chassis-channel of an automobile, of a side-spring supporting-hanger disposed on one side of said chassis-channel and bearing thereagainst, hanger-supporting means disposed on the other side of said chassis-channel, fastening connections between said hanger and said hanger-supporting means, and a filler-member disposed in said chassis-channel and comprising a top and bottom

and two ends, the latter projecting beyond the top and bottom, at one side thereof, to form lips bearing against said hanger-supporting means.

- 5 2. The combination with two longitudinal chassis-channels of an automobile, of a side-spring supporting-hanger disposed on one side of each of said chassis-channels and bearing thereagainst, hanger-supporting angle-bars disposed on the other side of each of said chassis-channels, fastening connections between each of said supporting-hangers and its adjacent angle-bars, a bridge

connecting said angle-bars and comprising two angle-bars resting, at their ends, upon the top of said first-mentioned angle-bars, reinforcing-plates interposed between said bridge angle-bars and said first-mentioned angle-bars, and securing means passing through said bridge-members and said reinforcing plates and through said first-mentioned angle-bars and said reinforcing plates.

15 20 In testimony whereof I hereunto affix my signature.

ANDREW J. BARRON.
